UNITED STATES PATENT OFFICE.

ROBERT F. DEERING, OF WASHINGTON, KANSAS, ASSIGNOR TO HIMSELF
AND MARTIN MCNITT, OF SAME PLACE.

FENCE-MACHINE.

SPECIFICATION forming part of Letters Patent No. 352,678, dated November 16, 1886.

Application filed July 8, 1886. Serial No. 207,460. (No model.)

To all whom it may concern:

Be it known that I, ROBERT F. DEERING, of Washington, in the county of Washington and State of Kansas, have invented a new and 5 Improved Fence-Machine, of which the following is a full, clear, and exact description.

The object of my invention is to provide a new and improved fence-machine for making a combined wire and picket fence of any de- 10 sired height and length.

The invention consists of various parts and details and combinations of the same, as will be fully described hereinafter, and then pointed out in the claims.

15 Reference is to be had to the accompanying drawings, forming a part of this specification, in which similar letters of reference indicate corresponding parts in all the figures.

Figure 1 is a plan view of my improvement 20 with parts of the fence-reel in section. Fig. 2 is a sectional side elevation of the same on the line $x-x$, Fig. 1. Fig. 3 is a vertical cross-section of the same on the line $y-y$ of Fig. 1. Fig. 4 is an enlarged sectional elevation of the twisting and tension devices. Fig. 5 is a plan view 25 of the same. Fig. 6 is a cross-section of the twisting-spindle, and Fig. 7 is a perspective view of the finished fence.

The different parts of the machine are 30 mounted on a frame, A, of suitable construction, and provided with a number of hollow twisting-spindles, B, placed in a horizontal plane and mounted in suitable bearings on the front part of the frame A. The spindles B are 35 connected with each other by gear-wheels C, meshing into each other and operated from a crank-arm, D, attached to one of the spindles B. Each spindle B is provided with two rectangular arms, B', placed opposite each other, 40 and each carrying a wire-reel, E, from which unwinds a wire, F or F', respectively, which passes through an aperture, B'', in the hollow spindle B, and along the inside of the spindle and out of the same through the aperture B'', 45 and thence to the tension device G, secured to the inner end of the spindle B.

The tension device G consists of the keepers H, each fastened to the spindle B, and having a longitudinal groove, H', through which passes 50 one of the wires F or F', and in which groove is guided the tension-spring plate I, the under-

bent ends of which rest on the said wires F or F', and through which passes centrally a screw, J, secured to the keeper H and provided on its outer end with a head or thumb-piece, J', 55 which screws upon the top of the spring-plate I. Directly below the tension device G is mounted on the frame A the beater-shaft K, provided with a number of beaters, K', and operated from one side of the frame A by a 60 crank-arm, K'', secured to the said shaft K.

The picket-gage or spacing device L consists of long and short adjustable rectangular rods M and M', each secured by two nuts to the cross-beam N, which slides vertically in the 65 guide O, attached to each side of the frame, and the cross-beam is also provided with downwardly-extending arms N', connected, respectively, with the arms P, secured to the oscillating shaft P', having its bearing in the frame 70 A, and provided with a spring, P'', one end of which is connected with the arm P, and its other end is connected with a cross-beam of the frame. The rod Q connects the cross-beam N with a foot-treadle, Q', pivoted to one side 75 of the frame A.

At the rear end of the frame A at the top is placed the loop-tightening device R, which consists of a stationary roller, R', and of a self-adjusting pressure-roller, R'', placed above 80 the roller R' and held in contact with the same by the springs R'', one end of each of which rests on the spindle of the roller R'', the other ends resting on the plate R', sliding in the guides R'', attached to the frame A. A set-screw, R'', screws on the said plate R', and serves to keep the tension of the spring R''.

On the beams A', extending from the rear of the frame A, is mounted, in suitable bearings, the reel-shaft S' of the reel S, which 90 shaft is provided with a number of slots, S'', (see Figs. 1 and 2,) through each of which passes an arm, S'', pivoted in the center of the reel-shaft S'. The arms S'' project on each side of the shaft S', and several arms, S'', are pivotally connected with each other on their outer ends by the cross-rods S''. On each end of the shaft S' is secured a ratchet-wheel, S'', which engages with a stop-pawl, S'', pivoted to the beam A', and also engages with a pawl, T, 100 pivoted to a crank-arm, T', on the shaft T'', provided with another crank-arm, T'', which

is connected by a link, T^4 , to the hand-lever U , placed on the front end of the machine.

On a post, A^2 , secured to the frame, in the center, near the front end, is pivoted a lever, V , on which is pivoted, on each side of the machine, an arm, V' , the lower end of which slides in the guides V^2 , secured to the inner faces of the uprights A^3 of the frame A . The lower end of each arm V' is provided with guide-rollers V^3 , between which passes a wire, W , which unreels from a reel, W' , mounted on a spindle, W^2 , secured to the frame A .

Between the inner ends of the spindles B and the tightening-rollers R' and R^2 are arranged a number of horizontal slats, A^4 , secured to the frame A between its respective sides, and supported by suitable cross-beams.

These slats form a table for the top of the machine, over which the fence passes.

20 The operation is as follows: When the machine is in the position shown in Fig. 1, the wires F and F' from the reels E form directly above the slats A^4 an opening between the tension device G and the first long gage-rod, M , so as to permit of the insertion of a picket, a , which is beaten against the stop of the gage-rod M by turning the crank-arm K' , which rotates the beaters K' . Then the operator turns the crank-arm D , whereby all the spindles B are rotated, and thereby form any desired number of twists in the wires F and F' between the picket a and the tension device G . After this is accomplished the operator presses on the treadle Q' , which moves the gage-rod M and M' downward and permits a forward motion of the fence, which motion is accomplished by pressing the lever U upward in the direction of the arrow a' , which causes the reel S to turn by means of the pawl T engaging the ratchet-wheel S' , and thereby winds up the fence. As soon as the picket a has passed the stop of the long rod M the operator releases the pressure on the treadle Q' , and the rods move back to their former position, as shown in Fig. 1, by the action of the springs P^2 on the arm P , which forces the cross-bar N upward. The forward movement of the picket a is thus interrupted as soon as the picket comes in contact with the stop of the short gage-rod M' . Another opening is now formed between the tension device and the stop of the long gage-rod M by the wires F and F' , and a new picket is inserted, and the above-described operation is repeated.

55 It will be seen that the bent ends of the spring-plate I of the tension device G rest on the respective wires F and F' , and the tension of the said spring-plate I can be increased or diminished by screwing the winged nuts J' down on the said plate, whereby the feed of the wires F and F' from the reels E is diminished or increased, and strong and good twists are formed between the pickets. Any size of wire can be used, as tensions can be placed on small wire as well as on large wire. As soon as the fence passes under the rollers R and R'

the rollers press the wires F and F' closely to and into the pickets, and the twists are also subjected to pressure to close them firmly. The fence is wound upon the reel S by coiling around the cross-bars S^4 , and when any desired length of fence is coiled on the said reel S , then the ratchet-wheels S^3 are removed from the shafts S' , and the arms S^3 are turned on their pivots, whereby the cross-bars S^4 move inward toward each other, and thereby free the coil of wire fence and permit the withdrawal of the reel from the interior of the coil of fence. The ratchet-wheels are then replaced on the beams A' .

An additional top and bottom wire can be attached to the fence from the reels W' , from which the wires pass up between the guide-rollers V^3 , and down and under the first picket, a , on one side of the machine, and over the same picket a on the other side of the machine, as one side of the guide-rollers V^3 is up above the spindles B while the other side is below the same. The position of the two wires W is alternately changed by the operator by moving the handle of the lever V up or down, whereby one set of the guide-rollers V^3 will rise above the spindles B , while the other descends below the same.

It will be seen that the operator can insert two or more pickets between the times of changing the relative positions of the wires W without interfering at all with the weaving of the fence. The wires W are secured to the pickets by staples or other devices, while the fence rests on the slats A^4 , and before entering the rollers R' and R^2 .

The object of placing barbed wire on the bottom of a low fence is to keep hogs from rooting under the fence, and in placing it on the top of a high fence is to prevent horses from biting off tops of pickets. By placing it on each side of a fence of four feet or more in height and dividing the fence in the middle by sawing in two I have two sections of short fence, and each section has a barbed wire on the bottom. The latter can be placed on high fences, if so desired.

Having thus described my invention, what I claim as new, and desire to secure by Letters Patent, is—

1. In a fence-machine, the combination of the twisting-spindles B with the screw-threaded right-angled gage-rod M and M' , having applied thereto upon each side of their supports adjusting-nuts, substantially as shown and described.

2. In a fence-machine, the combination of the twisting-spindles B with the adjustable gage-rod M and M' , the cross-beam N , and a device for raising and lowering the same, substantially as shown and described.

3. In a fence-machine, the combination of the twisting-spindles B , each provided with a tension device, G , with the adjustable gage-rod M and M' , the cross-beam N , carrying the said rods M and M' , and provided with an arm,

N', the arm P, attached to the shaft P', and the spring P², substantially as shown and described.

4. In a fence-machine, the reel S, consisting of the shaft S', having slots S², within which are pivoted the arms S³, and the cross-bars S⁴, substantially as shown and described.

5. In a fence-machine, the tension device G, attached to the hollow spindle B, and consisting of the keepers H, each having a groove, H', the spring-plate I, and the screw J, having a head or thumb-piece, J', substantially as shown and described.

6. In a fence-machine, the rotating hollow spindles B, each having apertures B² and B³, and being provided with arms B', each carrying a wire-reel, E, in combination with a ten-

sion device, G, attached to the hollow spindle B, and consisting of the keepers H, each having a groove, H', the spring-plate I, and the screw J, having a head or thumb-piece, J', substantially as shown and described.

7. In a fence-machine, the combination of the gage-rods M and M', the cross-beam N, having the downwardly-extending arms N', in combination with the arms P, attached to the shaft P', the spring P², operating on the said arm P, the rod Q, and the treadle Q', substantially as shown and described.
